UNITED STATES PATENT OFFICE.

ARTHUR REGINALD ANGUS, OF WESTMINSTER, LONDON, ENGLAND.

CONTROL OF TRAINS.

Application filed December 22, 1921. Serial No. 524,228.

To all whom it may concern:

Be it known that I, ARTHUR REGINALD ANGUS, a subject of the King of Great Britain and Ireland, and a resident of Westminster, in the county of London, England, have invented certain new and useful Improvements in or Relating to the Control of Trains, of which the following is a specification.

This invention, which consists of the improvements in train-controlling apparatus defined in the claims appended hereto is illustrated by the accompanying drawings, which represent diagrammatically examples of apparatus according thereto, Fig. 1 showing an example of track apparatus, Fig. 2 train apparatus suitable for use with the apparatus shown in Fig. 1, Fig. 3 train apparatus for speed control, and Fig. 4 track apparatus suitable for use in conjunction with the train apparatus shown in Fig. 3.

The apparatus shown in Fig. 1 is for controlling the passage of trains in both directions along a single track between two places A and B. The track is divided by insulations into sections and the rails of each side of the track are except where separated by insulation, conductively connected together. In order that for normal working a train located between insulations 118 and 6 near A may run towards B, a switch arm A' is moved so that inter alia its insulated contact 3 effects contact with a contact 4 so that current passes from a source of alternating current 1 by way of a wire 2, the contact 3 of the switch arm A', the contact 4, wire 5, to the rails 7, close to the insulation 6, by way of the rails 7, a wire 8, a contact 9, an insulated contact 10 of the switch arm A', a wire 11, two contacts 12 and 13 (which are normally bridged by a conductor or wire but may be connected together by a testing instrument), a wire 14, the primary winding 15 of a transformer TT, a wire 16, to the rails 18 near an insulation 17, by way of the rails 18, a wire 20, an insulated contact 21 of switch arm A', a contact 22, a wire 23, the primary winding 24 of a transformer TT¹, a wire 25 to the rails 26 near an insulation 19, by way of the rails 26, a wire 27, a contact 28, an insulated contact 29 of the switch arm A', a wire 30, the primary winding 31 of a transformer TT², a wire 32 to the rails 33 near an insulation 28, by way of the rails 33 to near an insu-

lation 55, thence by way of a wire 34, the primary winding 56 of a transformer TT³, a wire 35, a contact 36, an insulated contact 37 of the switch arm A', a wire 38, to rails 39 opposite to insulation 55, thence by way of the rails 39 to near to an insulation 40 thence by way of a wire 41, an insulated contact 42 (of the switch arm A'), a contact 43, a wire 44, and a wire 45 back to the source 1. If all is in order the energization of the said transformers TT, TT¹, TT², and TT³ will cause by induction the respective secondary windings 57, 58, 59, and 53 to be energized; each of the secondary circuits of these transformers may be provided with contacts, such as the contacts 12 and 13, for the insertion in parallel of testing instruments each of which, if the track be unoccupied and otherwise in order, will be affected by the state of the insulation relating to the corresponding primary so that it may be determined whether or not each relative insulation has broken down wholly or partially. The division of the track between the insulations 6 and 55 into sections by means of the insulations 17, 19, and 28 enables the signalman when this part of the track is occupied by a railway vehicle, to determine, by observing the testing instruments hereinbefore mentioned, the approximate location of the occupying vehicle. When all is in order and no railway vehicle is on any said section tested as above indicated then as the said primary winding 56 (of the said transformer TT³) is energized its relative secondary winding 53 has energy induced therein which passes by way of a wire 52 to a contact 801, an insulated contact 802 on the switch arm 719 (the contacts 801 and 802 being in contact if the switch arm 719, the function of which will be hereinafter described, is, as shown, in its neutral position), and a wire 805 to an electromagnet 51, thence by way of a wire 50, an insulated contact 49 (of the switch arm A'), a contact 48, a wire 47, the wire 44, the contact 43, the contact 42 on the switch arm A', and the wire 41, to the rails 39, and thence by way of wire 54, back to the secondary coil 53 of transformer TT³. A portion of the current supplied to the primary 56 of the transformer TT³ returns to the generator 1 by way of the wire 35, the contacts 36 and 37 the wire 38, the rails 39, the wire 54, the secondary winding 53 of the transform-

er TT^3 , the wire 52, the contacts 801 and 802, the wire 805, the electromagnet 51, the wire 50, the contacts 49 and 48 and the wires 47 and 45, but by suitably adjusting 5 the relationship between the resistance of this path and that of the main return path through the rails 39 this current can be made of such a value that its effect upon the energization of the electromagnet 51 is in- 10 appreciable. The energization of the electromagnet 51 causes its armature 46 to move so that it makes contact with a contact 181 and, inter alia, its insulated contact 75 effects contact with a contact 76 and current 15 passes from some suitable source of electricity 106 by way of a switch 109, a wire 77, the contact 76, the insulated contact 75 (of the armature 46), a wire 88, and a wire 91, to the rails 39 (opposite the insulation 118), thence along the rails 39 to a point 20 close to the insulation 40, thence by way of a wire 119, an insulated contact 120 (of the armature 46), a contact 121, a wire 122, and a wire 41, to the rails 39 (close to the insulation 40), thence along the rails 39 to a 25 point opposite the insulation 28, and thence by way of a wire 108 back to the source 106. As in consequence of the energization of the electromagnet 51 the armature 46 makes contact with the contact 181, current 30 flows through a circuit comprising the generator 1, the wire 2, the contact 3, a long contact with which the contact 3 is in contact, the armature 46, the contact 181, the 35 wire 182, the electromagnet 51, the wire 50, the contact 49, the long contact 48, and the wires 47 and 45, so that it is possible by moving the switch arm further to the right, while maintaining contact between the contacts 3 and 4 and their corresponding long contacts to break the circuits of the primaries of the transformers TT , TT^1 , TT^2 , and TT^3 , and at the same time to maintain the energization of the electromagnet 51 and 40 thus the circuit of the generator 106; the breakage of the circuits of the primaries of the transformers TT , TT^1 , TT^2 , and TT^3 interrupts the flow of testing current through 45 the rails 7, 18, 26, 33, and 39. The current 50 supplied to the train standing between the insulation 6 and 118 is adapted to prevent the production of a warning or stopping operation thereon by apparatus adapted to produce such an operation in the absence 55 of the flow therethrough of current suitable for restraining the production of such operation and thus permits the train to pass from A towards B up to the said insulation 28. One route for the transmission of current 60 to the apparatus on the train is thus provided in the manner hereinbefore described that route being adapted for the supply of current from the generator 106 through the portion of the rails 39 located 65 between points opposite to insulations 118

and 28. To enable the train to pass beyond the insulation 28 in the direction from A towards B, the railway track beyond the insulation 28 is provided with apparatus similar to that hereinbefore described. If the train 70 should attempt to pass beyond the insulation 28 when the road beyond this position is not made there will then be no electrical energy delivered to the rails beyond the insulation 28 (as by assumption this part of 75 the track has not had a road made thereon) and so a warning or stopping operation will be produced on the train.

The movement of said armature 46 (when its electromagnet 51 is duly energized) closes, inter alia, part of the circuit relating to a source of electricity 107 through a simple switch 110 (whereby the circuit relating to said source 107 may be independently opened and closed), so that 80 current flows from said source 107 by way of the switch 110, a wire 130, a contact 74, an insulated contact 73 (of the armature 46) and a wire 86 to the primary windings 93, 95, 96, and 99 of transformers TT^4 , TT^5 , 85 TT^6 , and TT^7 respectively, thence by way of a wire 131 to an earth plate 132, thence by way of earth to an earth plate 112 and thence by way of a wire 111 back to the source 107 and thus the relative secondary 90 windings 92, 94, 97 and 98 of said transformers TT^4 , TT^5 , TT^6 , and TT^7 respectively are energized and current flows as follows: (a) from the secondary winding 92 by way of a wire 133, to the rails 26 near 95 the insulation 19, thence along the rails 26 to a point near the insulation 28, thence by way of a wire 90, a contact 700, an insulated contact 80 (of the armature 46) and a wire 89 back to the secondary winding 92: (b) from the secondary winding 94 by way of a wire 134 to the rails 18 near the insulation 17, thence along the rails 18 to a point near the insulation 19, and thence by way of a wire 101, a contact 82, 100 an insulated contact 701 (of the armature 46) and a wire 100 back to the said secondary winding 94: (c) from the secondary winding 97 by way of a wire 135 to the rails 7 near the insulation 6, thence along 105 the rails 7 to a point near the insulation 17, and thence by way of a wire 103, a contact 83 an insulated contact 702 (of the armature 46) and a wire 102, back to the secondary winding 97; and (d) from the secondary 110 winding 98 by way of a wire 137 to rails 138 near the insulation 118, thence along the rails 138 to a point near the insulation 6, and thence by way of a wire 139, a contact 140, an insulated contact 141 (of the armature 46), and a wire 142 back to the secondary winding 98. Thus 115 when all is in order current for preventing the production on the train of a warning or stopping operation and so enabling the 120

train to proceed on the down journey—i.e., in the direction from A towards B—may be supplied to the rails on the side of the track opposite to the rails to which current 5 is supplied by the source 106; in this way a second route is provided for the transmission of current to the train apparatus.

Again in order to supply current for enabling a train to proceed on the down journey 10 by means of a conductor 906 placed suitably adjacent to the track rails a switch arm 143 is moved and current passes from a suitable source 142 by way of the switch arm 143, a wire 104, a contact 84, an insulated contact 85 (of the armature 46), and a wire 125 to the conductor 906, thence by way of the wire 144, to the earth plate 132, thence by way of the earth to an earth plate 146, and thence by way of a 15 wire 147 back to the source 142; in this way a third route is provided for the transmission of current to the train apparatus. The restraining apparatus on the train has suitable receiving means, as induction coils, 20 25 suitably placed in relation to the rails of each side of the track and to the conductor 906.

The operation of the switch arm A' and its connections for testing and making the road in the direction from B towards A are similar to those just described for testing and making the road in the direction from A towards B but the switch arm A' is for that purpose moved to the left and 30 35 the secondary of the transformer TT^o (used for up journey testing) which corresponds in function to the transformer TT^s is adapted to be connected by means of conductors that do not include rails to an electromagnet 175 (used for the up journey) which corresponds in function to the electromagnet 51 to which one pole of the secondary 40 45 53 of the transformer TT^s is adapted to be connected by way of the rails 39. For the up journey—i.e., for the journey in the direction from B towards A—the train is supposed to be located between the insulations 28 and 55 and the testing is effected 50 55 of the track from the insulation 28 to the insulation 118 and the train current is supplied from the insulation 55 to the insulation 6: for the up road the generators 188, 900, and 901 correspond respectively to the generators 106, 107, and 142 for the down road, and a conductor 902 extending along the track close to the rails of one side thereof corresponds to the conductor 906 for the down road.

In the example shown in Fig. 1, the 60 sources of electricity 1, 106, 107, 142, 188, 900, and 901 are sources of alternating current, the sources 106, 107, and 142 being adapted to supply alternating current of one frequency and the sources 188, 900, and 901 being adapted to supply alternating

current of another frequency and the apparatus on the trains being adapted to give clearance for the two directions of travel only when receiving current of the one or the other frequency that is appropriate to the direction of travel.

The current used for track testing should be different, as in strength or frequency, from current employed for giving clearance and should not be adapted to produce clearance operations.

In the example shown in Fig. 1 the insulations 6, 7, 19, and 28 are bridged by conductors containing primary coils the secondaries of which are in circuits each of 80 which is adapted to operate an instrument adapted to indicate the condition of the corresponding insulation or the presence of a train on a corresponding portion of the track and the supply of clearance current 85 may be controlled accordingly. Instead of there being primaries in the bridging conductors, those conductors may contain relays for the same purposes.

The presence of a vehicle on the portion or section of the track between the insulation 118 and 28 would normally, as hereinbefore described, prevent a train clearance current from being supplied to a locomotive so as to enable it to approach the vehicle on the 90 up journey because the vehicle would short-circuit the primary of the transformer TT^o or a corresponding relay the energization of which is necessary for the energization of the electromagnet 175 and the consequent 100 completion of a circuit for supplying clearance current to the locomotive. To enable the locomotive, notwithstanding the presence of the vehicle, to approach the vehicle along that portion of track, the switch arm 105 A' is restored to its neutral position and the switch arm 719 is moved so that its insulated contact 720 comes into contact with a contact 721 and its insulated contact 724 comes into contact with a contact 725 and thus a circuit is completed allowing current 110 to flow from an alternating-current generator 114, by way of a wire 115, and a wire 108, to the rails 39 opposite the insulation 28, thence along the rails 39 to a point near the insulation 40, thence by way of a wire 726, the contacts 724 and 725, and a wire 727 to the rails 39 on the other side of the insulation 40, thence along the rails 39 to a point opposite 115 the insulation 118, thence by way of the wire 91, a wire 117, a contact 728, an insulated contact 729 on the switch arm A' (only when the switch arm A' is, as shown, in the neutral position), a wire 723, the contacts 720 and 721, and a wire 722 back to the generator 114. The alternating current thus supplied to the rails by the generator 114 differs from the alternating current or currents normally supplied for giving the 120

125 currents normally supplied for giving the 130

locomotive clearance, and a clearance circuit on the locomotive will be closed partly owing to the abnormal position of a movable part of an instrument thereon that is 5 adapted to be energized by the alternating current induced in the said instrument by the current in the rails and partly owing to the abnormal position of a special switch which must for this purpose be moved by 10 the driver of the locomotive into the circuit-closing position. Similar means are provided, as shown, for enabling a locomotive to approach, on the down journey, a vehicle occupying the portion of track between the insulations 55 and 6.

In order that no train-clearance circuit may be made by the movement of the switch arm A' from its neutral position except when the switch arm 719 is in its 20 neutral position and that no train-clearance circuit can be made by the movement of the switch arm 719 except when the switch arm A' is in its neutral position, the circuits of the electromagnets 25 175 and 51 are adapted, as shown, to be closed by contacts carried by the switch arm 719 but to be so closed only when the arm 719 is in its neutral position—i. e., its neutral position in relation to the abnormal-working 30 circuits that it is adapted in conjunction with the switch arm A' to close for the purposes of this invention—and the abnormal circuits adapted to be closed by the switch arm 719 are adapted, as shown, to be so closed by contacts carried by the switch arm A' but to be closed only when the arm A' is in its neutral position—i. e., its natural position in relation to the normal-working 35 circuits that it is adapted to close.

40 The alternating train-clearance current caused by the generator 114 or the generator 113, according to the position of the switch arm 719 and to the direction in which it is desired that the locomotive shall 45 travel, to flow through the rails 39 as hereinbefore described, induces in an induction device 360 (which is shown diagrammatically in Fig. 2 as a single coil although it may, of course, comprise more than one 50 coil) of the train a corresponding alternating current which, by means of wires 361 and 377, flows to and from an instrument 382 having a movable part adapted, if the instrument be energized by currents of the 55 different frequencies to be employed, to occupy different positions respectively. When the instrument is energized by current of the frequency to permit the train to travel in the down direction its movable 60 part moves an arm 300 into a position in which its insulated contact plate 302 makes contact with a contact 801. A switch arm 803 is adapted to occupy a normal-working 65 position as shown in full lines in which it makes contact with a contact 909 and an ab-

normal-working position shown in dotted lines in which it makes contact with a contact 807 and into which it is moved by the driver of the locomotive when it is desired that the locomotive should approach a vehicle occupying a portion of track that the locomotive would normally be prevented from entering by its occupancy. When the switch arm 803 is in the abnormal-working position and the instrument 382 is energized as aforesaid, the production of a stopping operation is prevented if the speed of the locomotive does not exceed a certain low speed corresponding to a contact plate 333, whilst if that speed is exceeded the production of a stopping operation is no longer restrained and the locomotive is prevented from proceeding: if the speed of the locomotive does not exceed the aforesaid low speed, current flows from a generator 305 85 on the locomotive by way of a wire 306, an electromagnet 324 (which, when energized, is adapted to restrain by means of its armature 313 the production of a stopping operation), a wire 325, the switch arm 803, the 90 contact 807, a wire 320, an insulated contact 319 on an arm 318 the position of which depends on the speed of the locomotive, the contact plate 333 (in contact with the insulated contact 319 only when the speed of the 95 locomotive does not exceed the low speed to which the contact plate 33 corresponds), a wire 339, a contact 700 carried by but insulated from a switch arm 400 adapted to be in one or the other of two different positions 100 in accordance with the direction of running of the train (as by being connected with the reversing gear of the locomotive), a contact 379 with which the contact 700 is in contact when the reversing gear of the locomotive is set for the train to run in the 105 down direction, a wire 802, the contact 801, and back to the generator 305 by way of the insulated contact plate 302, and a wire 304: if the speed of the locomotive exceeds the 110 aforesaid low speed the arm 318 moves its insulated contact plate 319 out of contact with the contact plate 333 and thus breaks the circuit of the electromagnet 324 and a stopping operation is consequently produced on the locomotive. If the rails 39 are 115 not supplied with current for the abnormal working, the arm 300 (which when the instrument 382 is not energized is held by gravity against a stop) is not moved so as to bring its contact plate into contact with the contact 801, and, as, consequently, the electromagnet 324 is not energized, a stopping operation is produced on the locomotive.

120 During the normal-working for travel in the down direction the inducing current is of such a frequency as to cause the arm 300 to occupy a position in which its insulated contact plate 302 makes contact with a con- 125

tact 745 and the switch arm 803 is in the position indicated by full lines in Fig. 2; current consequently flows from the generator 305, by way of the wire 306, the electromagnet 324, the wire 325, the switch arm 803, the contact 909, a wire 910 a contact 701 carried by but insulated from the switch arm 400 a contact 378, a wire 746, the contact 745, the insulated contact plate 302, and back to the generator 305 by way of the wire 304, the production of a stopping operation thus being restrained.

The operation of the apparatus when the train is running in the up direction is similar to that described with reference to the down direction, the switch arm 400 being in the position in which its contacts 700 and 701 make contact with contacts 375 and 364 respectively when the reversing gear is set for the train to run in the up direction, and when the instrument 382 is energized by currents of frequencies to permit the train to travel in the up direction the arm 300 is moved so that its insulated contact plate 25 302 makes contact with a contact 805 for current of the frequency for abnormal working, and with a contact 747 for current of the frequency for normal working.

If it is not desired to limit the speed for the abnormal working, the wire 320 should be connected with the wire 339 directly and not, as shown, through the contact plates 319 and 333.

From the foregoing description of Figs. 1 and 2 it will be seen that the train apparatus includes danger indicating means (a warning device and/or a stopping device) adapted to come into operation unless electrically restrained, and the apparatus on the track, whereby a signalman is enabled to control the passage of the said train along a portion of track (e. g., the road extending between insulations 6 and 28 shown in Fig. 1), includes traffic-controlling electro-responsive means (for example, TT* of Fig. 1) adapted to be energized and de-energized by the movement of switching means by the signalman but to be prevented from being energized when either the said portion of track or the portion next in advance thereof (e. g., the section between insulations 28 and 55 shown in Fig. 1) is not in order, as by being occupied by a railway vehicle, and only when energized to cause the completion of a circuit for restraining the operation of the danger indicating device on the said train, and that for the purpose of increasing the control of the running of trains along the said portion of track I provide, on the track, apparatus to enable the signalman to cause currents differing (as of frequency) for the two directions of travel of trains to pass to the train apparatus, and, on the train, apparatus adapted to enable the electrical restraint of the operation of the

warning and/or the stopping device to be effected only when the current thus caused to pass is appropriate to the direction of travel for which the train is set; it will further be seen that, although the occupancy 70 of the said portion of track causes the de-energization of the traffic-controlling electro-responsive means, the said train itself is allowed to proceed along the said portion of track owing to the fact that I provide, as hereinbefore described, means (81, 122 of Fig. 1) for enabling the restraining circuit after being made by the traffic-controlling electro-responsive means to be maintained by the signalman.

It will also be seen that the train-controlling apparatus is adapted to enable a signalman and a locomotive driver to adjust the track and locomotive portions thereof (719 of Fig. 1 and 803 of Fig. 2) respectively to co-operative abnormal positions and thus to cause a portion (324 of Fig. 2) of the apparatus located on the locomotive to be energized by electricity and thereby to enable the locomotive to approach a vehicle occupying a portion of track, and that in order to impose a suitably low speed limit on the locomotive in this case, I provide means for causing a stopping operation to be performed on the locomotive if 95 the locomotive travel at a speed that is greater than a predetermined low speed, notwithstanding the adjustment of the track and locomotive portions of the train-controlling apparatus to the co-operative abnormal positions.

It will further be seen that, in the case of train-controlling apparatus comprising a train-carried device (313 of Fig. 2) the production by which of a danger indication 105 is dependent upon the condition as to electrification of apparatus (324 of Fig. 2) on the train, there are provided means adapted to furnish alternative independent track routes any one of which may at will be used 110 for transmitting current to affect the condition as to electrification of the aforesaid apparatus on the train as required in respect of the production of the danger indication so that the control of the train by 115 the aforesaid train-carried device in the normal manner can be produced from the track so long as any one of the said routes remain intact.

Fig. 3 shows train apparatus suitable for 120 use on a track comprising a portion along which it is intended to limit the speed of a train running thereover and which is divided by insulation into a warning section and a stop section, the warning section being one in which it is intended that a train travelling at a speed exceeding the pertinent speed limit should automatically have a warning operation or a service application 125 of the brakes produced thereon and the stop 130

section being one in which it is intended that such a train should automatically be stopped or have an emergency application of the brakes produced thereon. The rails 5 of the warning section being energized by alternating current of a frequency corresponding to the speed limit in question, as will hereinafter be described with reference to Fig. 4, this current induces in an induction device 360 (Fig. 3) (which is shown diagrammatically in the drawing as a single coil although it may, of course, comprise more than one coil) an alternating current of the same frequency, which, by 10 means of wires 361 and 377, flows to and from an instrument 382 having a movable part adapted to occupy certain definite and different positions if the instrument be energized by currents of the several frequencies to be employed respectively. The movable part of the instrument 382 has connected with it an arm 300 which consequently always occupies a position corresponding to the frequency of any current 15 for the time being energizing the instrument 382 and therefore corresponding also to the speed limit to which the frequency in question has been assigned. Thus when the instrument is energized by currents of 20 frequencies corresponding, for the restraint of a warning operation in the case of one direction of travel (hereinafter referred to as the down direction), to speed limits, of, for example, 15 miles an hour, 30 miles 25 an hour, and 45 miles an hour respectively, the arm 300 (which when the instrument 382 is not energized is held by gravity against a stop) occupies positions in which its insulated contact plate 301 makes contact with 30 contacts 346 and 347, contacts 343 and 344, and contacts 340 and 341 respectively. Corresponding respectively to the various speed 35 limits there are provided a pair of concentric contact plates 332 and 333 of equal angular extent, a pair of concentric contact plates 330 and 331 of equal angular extent, and a pair of concentric contact plates 328 and 329 of equal angular extent. All the concentric contact plates are insulated 40 from one another and the angular extents of the several pairs are limited to correspond to the respective speed limits. A speed-indicating part 318 the position of 45 which depends on the speed of the train carries insulated contact plates 314, 315, and 316 adapted to make contact with the contact plates 328, 330, and 332 respectively, and contact plates 322, 321, and 319 adapted to make contact with the contact plates 329, 331, and 333 respectively. An electro-magnet 310 is adapted when energized to prevent its armature 312 (which constantly tends to cause the production of a warning 50 operation or a service application of the brakes) from causing the production

of a warning operation or a service application of the brakes; and an electromagnet 324 is adapted when energized to prevent its armature 313 (which constantly tends to cause the production of a stopping operation or an emergency application of the brakes) from causing the production of a stopping operation or an emergency application of the brakes. When the train is on a warning section along which it is desired to limit its speed when running in the down direction to thirty miles an hour, the frequency of the current supplied to the track rails, by means hereinafter described with reference to Fig. 4, is such as to cause the arm 300 to occupy a position in which its insulated contact plate 301 makes contact with the contacts 343 and 344 which correspond to a speed limit of thirty miles an hour. If now the train is traveling at a speed not exceeding thirty miles an hour the speed-indicating part 318 occupies such a position that its insulated contact plate 315 makes contact with the contact plate 330 and, if a switch arm 400, adapted to be in one or the other of two different positions in accordance with the direction of running of the train (as by being connected with the reversing gear of the locomotive), is in the position corresponding to the down direction of running of the train which is that for which its contacts 700, 701, 702, 703, 704, 705, 706, and 707 are in contact with contacts 379, 378, 376, 375, 374, 373, 601, and 602 respectively, current flows from a generator 305 on the train along a wire 306 and thence (a) by way of a wire 309, the electromagnet 310, a wire 311, the contact plates 315 and 330, a wire 336, the contact 702 of the switch arm 400, the contact 376, a wire 326, the contact 343, the insulated contact plate 301, and wires 303 and 307 back to the generator 305, and (b) by way of a wire 308, the electromagnet 324, a wire 323, a wire 760, the contact 706 of the switch arm 400, the contact 601, the wires 503, 504, and 505, the contact 344, the insulated contact plate 301, and the wires 303 and 307 back to the generator 305. In this way a warning operation or a service application of the brakes is restrained by virtue of the travel of the train in the down direction at a speed that is not greater than the speed limit, for a train running in the down direction over that portion of the track, namely thirty miles an hour, whilst a stopping operation or an emergency application of the brakes is restrained independently of the speed of the train. If the speed of the train exceeds thirty miles an hour the speed-indicating part 318 occupies such a position that its contact plate 315 does not make contact with the contact plate 330 and consequently the described path through the electromagnet 130

net 310 is broken and a warning operation or a service application of the brakes is produced on the train, although for the reason above indicated the production of a stopping operation is prevented. If the driver of the locomotive fails to heed the warning and to act thereon, the train proceeds into the next succeeding section, which is the stop section hereinbefore mentioned. In connection with stop sections means (hereinafter described with reference to Fig. 4) are provided for supplying the rails thereof with alternating currents of frequencies, for the down direction of travel of the train, such as to cause the arm 300 to occupy positions in which its insulated contact 302 makes contact with contacts 730 and 348 only for a speed limit of fifteen miles an hour, with contacts 731 and 345 only for a speed limit of thirty miles an hour, and with contacts 732 and 342 only for a speed limit of forty-five miles an hour, the contact 301 not being in contact with any contact in any of these cases. If the speed limit for the portion of track is thirty miles an hour the arm 300 is in such a position that its insulated contact plate 302 makes contact with the contacts 731 and 345. If now the train is traveling at a speed not exceeding thirty miles an hour, the speed-indicating part 318 occupies such a position that its insulated contact plate 321 makes contact with the contact plate 331 and current from the generator 305 flows by way of the wire 306, the wire 308, the electromagnet 324, the wires 323 and 502, the insulated contact plate 321, the contact plate 331, a wire 337, the contact 703 of the switch arm 400, the contact 375, a wire 736, the contact 731, the insulated contact 302, and the wires 304 and 307 back to the generator 305. A stopping operation or an emergency application of the brakes is thus restrained by virtue of the travel of the train in the down direction at a speed that is not greater than the speed limit for a train running in the down direction over that portion of track, namely thirty miles an hour. Current from the generator 305 at the same time passes by way of the wires 306 and 309, the electromagnet 310, the wire 733, the contact 707 of the switch arm 400, the contact 602, and the wires 506, 507, and 508 to the contact 345 and thence by way of the contact 302 and the wires 304 and 307 back to the generator 305 so that the electromagnet 310 is energized and the warning operation is consequently restrained; the warning operation is similarly restrained when the contact 302 is in contact with any of the other pairs of contacts to which it relates. If the speed of the train exceeds thirty miles an hour the speed-indicating part 318 occupies such a position that its contact plate 321 does not make contact with

the contact plate 331 and consequently the described path through the electromagnet 324 is broken and a stopping operation or an emergency application of the brakes is consequently produced on the train. 70

The track rails of a portion of track in which it is not desired to limit the speed of a train running in the down direction—for example, that portion of the track over which the train runs on leaving a curve—75 are energized by alternating current of a frequency such as to cause the arm 300 (Fig. 3) to be moved into the position in which its insulated contact plate 302 makes contact with contacts 900 and 901; in this case current flows from the generator 305 through a wire 306 thence (a) by way of the wire 309, the electromagnet 310, the wire 733, the contacts 707 and 602, the wires 506 and 507, a wire 905, the contact 901, the contact plate 302, and the wires 304 and 307 back to the generator 305 and (b) 80 by way of the wire 308, the electromagnet 324, the wires 323 and 760, the contacts 706 and 601, the wires 503 and 504, a wire 904, 85 the contact 900, the contact plate 302, and the wires 304 and 307 back to the generator 305. Thus the energization of the electromagnets 310 and 324, and consequently the restraint of both a warning operation and a stopping operation, is effected on the train by circuits which do not include any of the concentric contact plates 328 to 333 inclusive so that the restraint of both warning and stopping operations is in this case independent 90 of the speed of the train. 95

In order to enable the magnets 310 and 324 to exercise their restraint while the arm 300 is moving from one speed-limiting position to another they may be rendered slow-acting as by providing them with shunts 709 and 710 respectively containing suitable non-inductive resistances. 105

For controlling the running of a train in the up direction alternating currents of a different set of frequencies are supplied to the track rails, and the alternating currents consequently induced in the device 360 (Fig. 3) corresponding to speed limits of fifteen miles an hour, thirty miles an hour, and forty-five miles an hour are such as to move the arm 300 so that its insulated contact plate 301 makes contact with contacts 350 and 353, contacts 352 and 357, and contacts 354 and 366 respectively when the train is in a warning section, and with contacts 740 and 351, contacts 742 and 355, and contacts 744 and 359 respectively when the train is in a stop section, the contacts 350, 352, 354, 740, 742, and 744 being connected with contacts 752, 754, 756, 751, 753, and 755 respectively, with which the contacts 700, 701, 702, 703, 704, and 705 of the switch arm 400 make contact when the reversing gear of the train is set for the train to run 110 115 120 125 130

in the up direction, and the contacts 351, 355, and 359 being connected with the contact 605, and the contacts 353, 357, and 366 being connected with the contact 604, and the contacts 706 and 707 of the switch arm 400 being adapted to be in contact with the contacts 604 and 605 respectively when the reversing gear of the train is set for running in the last mentioned direction.

10 The alternating current supplied to the track rails to enable a train to travel at an unlimited speed in the up direction differs from that supplied for enabling a train to travel at an unlimited speed in the down direction and is of such a frequency as to cause the arm 300 (Fig. 3) to be moved so that its contact plate 302 makes contact with contacts 902 and 903 which are connected by wires 906 and 907 with the contacts 605 and 604 respectively, and the restraint of both a warning operation and a stopping operation is effected on the train, if the switch 400 is in the position corresponding to the up direction of running, in 20 a manner similar to that described with reference to the down direction of running.

It will be seen that if the switch arm 400 (Fig. 3) is in a position that is not in agreement with the direction in which it is intended that trains should run along the track no circuit is completed through either of the restraining magnets 310 and 324 because the contacts with which the insulated plates 301 and 302 of the arm 300 are in contact are not, owing to the position of the switch arm 400, electrically connected to the contacts of the switch arm and consequently neither a warning nor a stopping operation is restrained on the train.

40 Fig. 4 shows a part of a track including a curve equipped with apparatus adapted to control the speed and direction of running of a train provided with the apparatus such as that shown in Fig. 3 when passing over the curve in either direction. The apparatus is adapted (a) to impose a certain speed limit upon a train running along the portion of track between an insulation 54 and an insulation 58 in the down direction (from the insulation 54 towards the insulation 58), this portion being for that purpose divided by an insulation 56 into a warning section and a stop section (namely, the section I between the insulations 54 and 56 and the section II between the insulations 56 and 58), (b) to allow that train to travel at an unlimited speed between the insulations 58 and 62, (c) to impose a certain speed limit upon a train running in the up direction along the portion of track between the insulations 62 and 58, that portion being similarly divided into a warning section (section III) and a stop section (section IV) by the insulation 60, and (d) to allow the last mentioned

train to travel at an unlimited speed between the insulations 58 and 54. The track rails are adapted to be energized by alternating currents of the several different frequencies necessary to effect this control 70 from the sources of alternating current 1, 2, 3, 4, 5, and 6 as will now be described.

To set the track apparatus to control the running of a train in the down direction a switch arm A (Fig. 4) is moved to the left 75 so that contacts 31 and 39, 43 and 51, 19 and 27, and 8 and 16 carried by but insulated from the arm A effect contact with contacts 32 and 38, 44 and 50, 20 and 26, and 9 and 15 respectively, and current flows, inter alia, 80 from the source 3 by way of a wire 7, the contacts 8 and 9, and wires 10 and 11 to rails 12 of section I at a point near the insulation 56, thence along the rails 12 to a point near the insulation 54, thence by way 85 of wires 13 and 14, the contacts 15 and 16 and a wire 17 back to the generator 3; current at the same time passes from the source 2 by way of a wire 18, the contacts 19 and 20, and wires 21 and 22 to the rails 90 23 of section II at a point near the insulation 58, thence along the rails 23 to a point near the insulation 56, and thence by way of wires 24 and 25, the contacts 26 and 27, and a wire 28 back to the source 2. The sources 95 3 and 2 are adapted to supply alternating currents of frequencies corresponding to the speed limit assigned to sections I and II and also to the down direction of running of a train, and such as to cause sections I and 100 II to act as warning and stop sections respectively; if the limit of speed is 30 miles an hour, as in the case of the example described with reference to Fig. 3, the frequency of the current supplied from the 105 source 3 (Fig. 4) to the rails 12 of section I is such as so to energize the instrument 382 (Fig. 3) of a train running thereover that its arm 300 moves into the position in which its contact plate 301 makes contact with the 110 contacts 343 and 344, and the frequency of the current supplied from the source 2 (Fig. 4) to the rails 23 of section II is such as to cause the arm 300 (Fig. 3) to be moved into the position in which its contact plate 115 302 makes contact with the contacts 731 and 345. Current also passes from the source 1 (Fig. 4) along a wire 29, thence (a) by way of a wire 30, the contacts 31 and 32, and wires 33 and 34 to rails 35 of 120 section IV at a point near the insulation 60, thence along the rails 35 to a point near the insulation 58, and thence by way of wires 36 and 37, the contacts 38 and 39, and wires 40 and 41 back to the source 1, and (b) by 125 way of a wire 42, the contacts 43 and 44, and wires 45 and 46 to rails 47 of section III at a point near the insulation 62, thence along the rails 47 to a point near the insulation 60, and thence by way of wires 48 and 49, 130

the contacts 50 and 51, a wire 52, and the wire 41 back to the source 1. The rails 35 and 47 of sections IV and III are thus traversed by alternating current from the source 1, which supplies current of such a frequency as to enable a train running in the down direction to travel at an unlimited speed, i. e., of such a frequency as to cause the instrument 382 (Fig. 3) on the train 10 to be so energized as to move its arm 300 so that its contact plate 302 makes contact with the contacts 900 and 901. Thus the apparatus on the track (Fig. 4) is adapted to control the passage of a train approaching the curve in the down direction from the insulation 54 to the insulation 62 so that if the train exceeds the speed limit assigned to sections I and II on section I a warning operation is effected thereon, if it exceeds 20 that speed limit on section II a stopping operation is effected thereon, and so that the train may run at an unlimited speed away from the curve over sections IV and III.

25 To control the passage of a train when running in the up direction the switch arm A (Fig. 4) is moved to the right so that other contacts carried thereon but insulated therefrom make contact with another set of contacts and thus cause the completion of circuits which are similar to those described with reference to the control of a train running in the down direction, and which enable the sources 6 and 5 to supply currents of frequencies, corresponding to the speed limit assigned to the sections IV and III for the up direction of running, to the rails of the last mentioned sections, the frequencies being such as to make the sections a warning section and a stop section respectively, and the source 4 to supply current to the rails of sections II and I of a frequency to permit a train to travel at an unlimited speed when running over the last mentioned sections in the up direction.

It is obvious that the parts of the track beyond the insulations 54 and 62 (Fig. 4) may be adapted so that a train may travel thereover at an unlimited speed, the rails thereof being energized for that purpose with alternating currents of the corresponding frequencies either from the sources 4 and 1 respectively or from similar sources located elsewhere, and that apparatus for controlling the speed of a train at any other parts of the track where it may be desired may be provided at those parts and the sources corresponding to the sources 2, 3, 5, and 6 adapted to supply alternating currents of the frequencies corresponding, for the two directions of travel of a train, to the speed limits that it is desired to impose upon a train when running over those parts.

Instead of employing alternating currents of differing sets of frequencies for the op-

posite directions of travel, alternating currents of one set of strengths may be employed for permitting and controlling the running of trains in the down direction and alternating currents of another set of strengths employed for permitting and controlling the running of trains in the up direction: the instrument 382 (Figs. 2 and 3) being then adapted, when energized by currents of various strengths induced by the track currents of the several strengths employed respectively, to cause its arm 300 to make contact with its several contacts respectively as hereinbefore described with reference to currents of the several frequencies mentioned.

In Figs. 2 and 3 the induction device 360 is diagrammatically represented as a single coil only but in order to obtain the best results there should be placed on the locomotive and also if required on a vehicle or vehicles attached thereto a number of coils which may extend all along the locomotive and should be placed as close as practicable to the track rails and/or the conductor arranged close thereto and of course on both sides of the locomotive if the rails on both sides of the track are to be employed.

In the case of the apparatus described with reference to Fig. 3 it will be seen that when current commences to flow through the electromagnet 310 and thus to cause its energization current also flows from the wire 309 by way of a path the completion of which was caused by the last previous de-energization of the electromagnet 310 and which comprises a wire 390, a contact 391, a resilient contact 392, a wire 394, a line-clear bell or buzzer 712, and a wire 395, to the wire 733, and a line-clear indication is thus given which is caused to cease by the interruption of this path when the armature 312 moves in consequence of the energization of the electromagnet 310 and removes the resilient contact 392 from the contact 391 by moving the arm 393; alternatively the circuit of the line-clear bell or buzzer can be broken after the completion of the circuit of the battery 305 by other means as by pressure of a push button by the driver.

When the invention is used in connection with electric trains the current supplied to the track rails for the purposes of this invention should, of course, so differ from the propulsion current as not to be interfered with thereby as far as the operations hereinbefore described are concerned—for example, if alternating or pulsating unidirectional current at one frequency is used for the propulsion, alternating or unidirectional pulsating current at frequencies different from that used for propulsion should be used for the train-controlling currents and, except in the case of the conductor parallel to the track, train-controlling currents are

preferably supplied by means of transformers or induction coils at a higher voltage or voltages than the propulsion current.

I claim:—

- 5 1. Electrical train-controlling apparatus comprising on a train apparatus including a danger-indicating device adapted to come into operation unless electrically restrained and on the track apparatus for enabling a
- 10 signalman to control the passage of said train along a portion of track including switching means and traffic-controlling electro-responsive means adapted to be included in circuit and excluded from circuit
- 15 by said switching means, to be energized when so included in circuit and both said portion of track and the portion next in advance are unoccupied by a railway vehicle and then to cause the completion of a circuit for
- 20 for restraining the operation of said danger-indicating device on said train, and to be de-energized both when excluded from circuit and when either of said portions of track is occupied by a railway vehicle, substantially as described.
- 25

2. Apparatus according to claim 1 comprising means adapted to enable said restraining circuit after being made as aforesaid to be maintained by the signalman so that the restraint of the operation of said danger-indicating device can be maintained during the passage of said train along said portion of track notwithstanding the de-energization of said traffic-controlling electro-responsive means, substantially as described.

3. Electrical train-controlling apparatus comprising on a train apparatus including a danger-indicating device adapted to come into operation unless electrically restrained from the track and on the track apparatus for enabling a signalman to control the passage of said train along a portion of track including switching means, traffic-controlling electro-responsive means adapted to be included in circuit and excluded from circuit by said switching means, to be energized when so included in circuit and said portion of track is unoccupied by a railway vehicle and then to cause the completion of a circuit for restraining the operation of said danger-indicating device on said train, and to be de-energized both when excluded from circuit and when said portion of track is occupied by a railway vehicle, and means adapted to enable said restraining circuit after being made as aforesaid to be maintained by the signalman so that the restraint of the operation of said danger-indicating device can be maintained during the passage of said train along said portion of track notwithstanding the de-energization of said traffic-controlling electro-responsive means, substantially as described.

- 70 4. Electrical train-controlling apparatus

comprising on a train apparatus including a danger-indicating device adapted to come into operation unless electrically restrained and on the track apparatus for enabling a signalman to control the passage of said train along a portion of track including switching means, traffic-controlling electro-responsive means adapted to be included in circuit and excluded from circuit by said switching means to be energized when so included in circuit and both said portions of track and the portion next in advance are unoccupied by a railway vehicle and then to cause the completion of a circuit for restraining the operation of said danger-indicating device on said train, and to be de-energized both when excluded from circuit and when either of said portions of track is occupied by a railway vehicle, and means adapted to enable the signalman, by moving said switching means after the completion of said restraining circuit, to exclude said traffic-controlling electro-responsive means from circuit and at the same time to maintain said restraining circuit, substantially as described.

5. Electrical train-controlling apparatus comprising on a train apparatus including a danger-indicating device adapted to come into operation unless electrically restrained from the track and on the track apparatus for enabling a signalman to control the passage of said train along a portion of track including switching means, traffic-controlling electro-responsive means adapted to be included in circuit and excluded from circuit by said switching means, to be energized when so included in circuit and said portion of track is unoccupied by a railway vehicle and then to cause the completion of a circuit for restraining the operation of said danger-indicating device on said train, and to be de-energized both when excluded from circuit and when said portion of track is occupied by a railway vehicle, and means adapted to enable the signalman, by moving said switching means after the completion of said restraining circuit, to exclude said traffic-controlling electro-responsive means from circuit and at the same time to maintain said restraining circuit, substantially as described.

6. Electrical train-controlling apparatus comprising on a train apparatus including a danger-indicating device adapted to come into operation unless electrically restrained and on the track apparatus for enabling a signalman to control the passage of said train along a portion of track including switching means, traffic-controlling electro-responsive means adapted to be included in circuit and excluded from circuit by said switching means, to be energized when so included in circuit and both said portion of track and the portion next in advance are

unoccupied by a railway vehicle and then to cause the completion of a circuit for restraining the operation of said danger indicating device on said train, and to be de-
5 energized both when excluded from circuit and when either of said portions of track is occupied by a railway vehicle, and means adapted to enable the signalman to cause currents differing (as in frequency) for the
10 two directions of travel of trains to pass to said apparatus on said train, said apparatus on said train being adapted to enable the electrical restraint of the operation of said danger-indicating means to be effected only
15 when the current thus caused to pass is appropriate (as in frequency) to the direction of travel for which said train is set, substantially as described.

7. Electrical train-controlling apparatus comprising on a train apparatus including a danger-indicating device adapted to come into operation unless electrically restrained from the track and on the track apparatus for enabling a signalman to control the passage of said train along a portion of track including switching means, traffic-controlling electro-responsive means adapted to be included in circuit and excluded from circuit by said switching means, to be energized
25 when so included in circuit and said portion of track is unoccupied by a railway vehicle and then to cause the completion of a circuit for restraining the operation of said danger-indicating device on said train, and to be de-
30 energized both when excluded from circuit and when said portion of track is occupied by a railway vehicle, means adapted to enable said restraining circuit after being made as aforesaid to be maintained by the
35 signalman so that the restraint of the operation of said danger-indicating device can be maintained during the passage of said train along said portion of track notwithstanding the de-energization of said traffic-controlling
40 electro-responsive means, and means adapted to enable the signalman to cause currents differing (as in frequency) for the two directions of travel of trains to pass to said apparatus on said train, said apparatus on said train being adapted to enable the electrical restraint of the operation of said danger-indicating means to be effected only
45 when the current thus caused to pass is appropriate (as in frequency) to the direction of travel for which said train is set, substantially as described.

8. Electrical train-controlling apparatus comprising a warning device and a stopping device each adapted to come into operation
50 when not under electrical restraint, a speed-responsive part adapted to change its position in accordance with the speed of the train, and a speed-limiting electromagnetic device adapted in accordance with its energization by specific different currents cor-

responding respectively to specific different speed limits, to cause its movable part to occupy specific different speed-limiting positions, there being two specific different currents for a specific speed limit and cor-
70 respondingly two different speed-limiting positions of the said movable part in the first of which it is adapted by itself to cause the electrical restraint of the operation of said stopping device but to co-operate 75 with said speed-responsive part in causing the electrical restraint of the operation of said warning device only when said speed-responsive part is occupying a position that corresponds to a speed not greater than the speed limit represented by the position for the time being of said movable part and in the second of which it is adapted to co-operate 80 with said speed-responsive part in causing the electrical restraint of the operation of said stopping device only when said speed-responsive part is occupying a position that corresponds to a speed not greater than the speed limit represented by the position for the time being of said movable part, and on the track and in connection with specific different parts thereof energizing means adapted to cause said speed-limiting electromagnetic device to be energized
85 by said specific different currents at 90 said specific different parts respectively, a specific part of the track including both a warning section in which said energizing means is adapted to cause said speed-limiting electromagnetic device to be energized 95 by current such as to cause said movable part to occupy said first position and also a stop section in which said energizing means is adapted to cause said speed-limiting electromagnetic device to be energized 100 by current such as to cause said movable part to occupy said second position.

9. Electrical train-controlling apparatus comprising on a train a danger-indicating device adapted to tend constantly to produce a danger-indicating operation, electro-magnetic restraining means adapted when energized to restrain the operation of said danger-indicating device, a speed-responsive part adapted to change its position in accordance with the speed of the train, a speed-limiting electromagnetic device adapted, in accordance with its energization by specific different currents corresponding respectively to specific different speed 110 limits, to cause its movable part to occupy specific different speed-limiting positions, a direction-corresponding part adapted to change its position in accordance with the direction of running of the train, and current-receiving means adapted to be energized by track current and when energized to cause the energization of said speed-limiting electromagnetic device, and on the track 115 and in connection with specific different 120 currents

parts thereof energizing means adapted to cause said current-receiving means to be energized by specific different currents in different pairs whereof each corresponds to a 5 specific speed limit and the members of each differ in accordance with the direction in which it is intended that said train should run, said speed-responsive part, said movable part of said speed-limiting electromagnetic device, and said direction-corresponding part being adapted to co-operate in including said electromagnetic restraining means electrically in circuit and so causing its energization only when said speed- 10 responsive part is occupying a position that corresponds to a speed not greater than the speed limit corresponding to the position for the time being of said movable part of said speed-limiting electromagnetic device 15 and said direction-corresponding part is in a position corresponding to the current for the time being energizing said current-receiving means and consequently to the direction in which it is intended said train 20 should run.

10. In train controlling apparatus comprising a train-carried device the production of a danger indication by which is dependent upon the condition as to electrification 25 of apparatus on the train, means adapted to provide alternative independent track routes any one of which may be used for

transmitting current to affect the condition as to electrification of said apparatus on the train as required in respect of said danger 35 indication so that the control of the train by said train-carried device in the normal manner can be produced from the track as long as any of said routes remain intact, substantially as described. 40

11. Electrical train-controlling apparatus comprising an electromagnetic device adapted when de-energized to allow its movable part to produce a danger-indicating operation, energizing means for energizing said electromagnetic device, an electrically operable line-clear indicator, and means adapted to enable said movable part, when said electromagnetic device is de-energized, to complete a current path including said line-clear indicator and adapted when completed to connect said line-clear indicator in circuit with said energizing means so that on the subsequent energization of said electromagnetic device said line-clear indicator will be operated by current flowing through said path from said energizing means, said current path being adapted to be broken after the energization, and until the next de-energization, of said electromagnetic device, substantially as described. 50

Signed at London, England, this 9th day of December, 1921.

ARTHUR REGINALD ANGUS.
